UNITED STATES PATENT OFFICE.

WILLIAM M. SCOTT, OF PHILADELPHIA, PENNSYLVANIA, ASSIGNOR TO THE CUTTER ELECTRICAL AND MANUFACTURING COMPANY, A CORPORATION OF NEW JERSEY.

REMOTE CONTROL SYSTEM.

1,106,116.

Specification of Letters Patent.

Patented Aug. 4, 1914.

Application filed April 23, 1907. Serial No. 369,714.

To all whom it may concern:

Be it known that I, WILLIAM M. SCOTT, a citizen of the United States, residing at Philadelphia, in the county of Philadelphia and State of Pennsylvania, have invented a new and useful Remote Control System, of which the following is a specification.

For an illustration of a form my invention may take reference is to be had to the accompanying drawings, in which:

Figure 1 is a side elevational view of the circuit breaker and its operating and control mechanism, a portion of the motor operated mechanism being omitted. Fig. 2 is a front elevational view of the circuit breaker and its operating and control mechanism. Fig. 3 is a front elevational view, partly in section, of the joint between the connecting rod and the circuit breaker operating lever. Fig. 4 is a side view, partly in section, of the connecting rod connection with the motor operated mechanism. Fig. 5 is a detail view of the driving and driven cranks. Fig. 6 is a diagrammatic view of the control system.

Referring to said drawings, 1 represents a base of suitable insulating material such as slate, marble, or the like, upon which are secured the main circuit breaker contact blocks 2 and 3 bridged by the laminated movable contact 4 secured to, but insulated from, the arm 5 pivoted at 6 to the bracket or housing 7, which is secured upon the base 1.

8 and 9 are the metallic and carbon movable shunt contacts respectively which cooperate respectively with the stationary metallic and carbon shunt contacts 10 and 11. The contacts 8 and 9 are carried by but insulated from the pivoted arm 5 which carries the laminated contact 4. Pivoted at 12 in the arm 5 is a roller 13, which is engaged by the cam surface 14 on the cam member 15 pivoted to the bracket 7 at 16. The cam member extends outwardly beyond the pivot 16 as shown at 17. The operator's handle or lever 18 is pivoted at 19 on the extension 17 of the cam member and is capable of limited movement upon the extension 17. The extent of movement is limited by the surfaces 20 and 21 as to a counter-clockwise movement and by the surfaces 22 in a clockwise direction.

Secured to or integral with the operator's

lever 18 in an inwardly extending lug 23 whose tail 24 is adapted, upon counter-clockwise movement of the operator's handle 18 upon the pivot 19, to strike the projection 25 of the latch 26 pivoted to the housing at 27, and engaging by its hook end the roller 28 pivoted at 29 in the member 17. The contacts are held in circuit closing position, as shown in Fig. 1, by the latch 26 restraining the cam member 15. Besides being operated by the lug 23, the latch 26 is adapted to be operated by the latch actuating member 30 pivoted at 27 and having a rearward extension 31 against whose underside the pivoted armature 32 of an overload tripping magnet is adapted to strike. The latch 26 is also operated by the rod 33 connected to the armature of the reverse current or reverse energy tripping coils 34.

Extending transversely through the operator's lever 18 is a pin 35 which fits within the metal bushing 36 within the insulating bushing 37, which latter is secured within the eye 38 upon the rod 39. The insulating bushing 37 serves to insulate the rod 39, and the parts connected thereto below, from the operator's handle and, in fact, from the entire circuit breaker. The rod 39 carries the transversely extending pin 40 which plays substantially vertically in the slot 41 in the bifurcated head 42 screw threaded upon the connecting rod or pitman 43. The rod 43 is screw threaded at its lower end into the member 44 having extension 45. The extension 45 and plate are held together by the bolts 47, the separators 48 intervening. Approximate their lower ends, the extension 45 and plate 46 have spherical depressions or sockets adapted to embrace the ball 49 formed upon or secured upon the crank pin 50. This construction forms a universal joint between the crank pin and the connecting rod 43, which, with the pin connection 40, obviates the necessity for exact mechanical alinement between the circuit breaker and the motor driven apparatus about to be described.

The crank pin 50 is common to the two cranks 51 and 52. The crank 51 is secured upon the shaft 53 having a bearing 54 upon the base 55. On the other end of the shaft 53 is secured the crank 56 which is in the path of travel of the crank 57 secured upon

the shaft 58 having the bearings 59 and 60 upon the base 55. Secured upon the shaft 58 between the bearings 59 and 60, is the worm wheel 61 which meshes with the worm 62 secured upon the shaft 63 of the electric motor M, mounted upon the base 64. The worm 62 terminates at its outer end in a conically socketed member 65, whose inner conical surface is the surface of what may 10 be termed a brake wheel.

66 is a conically surfaced brake shoe pivoted at 67 to the bifurcated lever 68 which is in turn pivoted at 69 to the base 55. The upper end of the lever 68 has a transversely 15 extending member 70 to whose ends 71 are connected spiral springs 72 connected at their other ends to ears 73 upon opposite sides of the iron magnet jacket or housing 74, which is supported by brackets 75 and 20 76 upon the frame of the motor M. Within the jacket 74 is a magnet core 77 pierced horizontally and axially to permit the passage of the rod 78 which presses with its outer end against the lever 68 and which is 25 secured at its inner end to the armature 79 of the magnet, which is the brake lifting magnet whose winding 80 is disposed between the core 77 and the inside of the jacket 74.

30 The inner end of the crank 52 is secured to the disk 81 of insulating material, such as hard fiber. That disk, with a similar disk 82 and the commutator rings or segments 83 and 84, rotate, as driven by the 35 crank 52, upon the shaft 85 secured upon the plate 86, of slate or other suitable insulating material, which is in turn secured upon the riser 87 on the base. The brush 88 bears upon the ring 83, while the brush 40 89 bears upon the ring 84, the brushes 88 and 89 being suitably held but insulated from each other by the holder 90.

Referring to the diagram in Fig. 6, 91 and 92 represent the bus bars or other conductors of a power, lighting, or other electric circuit. A connection is made from the bus bar or conductor 92 by the conductor 93 to the brush 88, which bears on commutator ring 83, and from the conductor 91 by conductor 94, through the laminated bridge 4 of the circuit breaker such as shown in Fig. 1. The generator G is connected across the conductors 91 and 92 when the circuit breaker is in circuit closing position. 50 G is a generator, or other source of energy, or motor, or other translating device, whose connection with the conductors 91 and 92 is to be controlled both automatically by the circuit breaker and from a distance by the 55 switch 95, as hereafter described. The conductor 94 connects also with the brush 89 which bears upon the commutator ring or segment 84. The circumference of the ring 83 is not continuous, but is interrupted by insulating material 83', there being also a sudden drop,

as at 83'' for causing a sudden break in the circuit, and similarly, the circumference of the ring 84 is discontinuous, made so by the insulating material 84'. The rings 83 and 84 are in electrical communication with the 70 shaft 85 from which leads the conductor 96 to one brush of the armature Ma of the motor M; the other brush connects by conductor 97 with one terminal of the series field winding Sf of the motor M, in parallel with which is connected the winding 80 of the brake lifting magnet. The other terminal of the series field is joined by conductor 98, which extends to the distant station from which the control is to be effected, to the switch 95, located at the distant control station. The switch member 95 is adapted to rest upon any one of the three contacts 99, 100, or 101, of which 99 may be connected to a positive conductor of the system 80 through the winding of underload magnet 102, while 101 may be connected to a negative conductor of the system through the winding of the underload magnet 103. L 85 is an ordinary incandescent lamp connected between the contacts 99 and 100 to serve as an indicator.

The operation of the system and apparatus is as follows: With the circuit breaker in circuit closing position, as shown in Figs. 95 1 and 2, upon the occurrence of an abnormal current flow through the circuit breaker, or upon the occurrence of reversed current or reversed energy flow, the latch 26 will be actuated either by the armature 32 of the 100 overload magnet or by the rod 33 of the reversed energy flow tripping mechanism, to release the member 17. Upon such release the spring 15' will contract and rotate the cam member 15 in a counter-clockwise direction about its pivot 16, as viewed in Fig. 1. The laminated contact member 4 will then 105 separate from the main terminal blocks 2 and 3, thereafter the metallic shunt contact 8 will separate from the metallic shunt contact 10, and finally the carbon 9 will separate from the carbon 11, and at these carbons the final arcing will occur in the manner well understood in the circuit breaker art. As the cam member rotates, as described, about the 110 pivot 16, the operator's handle 18 raises the connecting rod 43 and rotates the cranks 51 and 52 to a position just short of dead center, just to the left of the uppermost position they can take as viewed in Fig. 1. To prevent reaching or passing the upper dead center, an extension 57' is provided on driving crank 57, and the lug 57'' thereon extends into the path of the driven crank 56, as seen in Fig. 5. The generator or other device G has then been cut off by the opening 115 of the circuit breaker from communication with the bus bars or conductors 91 and 92, and the crank 52 has rotated the commutator rings 83 and 84 to such position that the 120 125 130 135 140 145 150 155 160 165 170 175 180 185 190 195 198

brush 88 has again come into contact with the commutator ring 83 after traversing the insulation 83'. The switch 95, at the distant station being on the contact 100, there is a circuit from the positive conductor through magnet 102 to contact 99 through lamp L, contact 100, switch lever 95, conductor 98, brake winding and field winding and motor armature, through conductor 96, through commutator ring 83, brush 88 to conductor 92. The lamp in such case will glow indicating that the apparatus is in position to be motor operated to close the breaker. The operator then throws the switch 95 onto contact 99, the armature 104 being held by magnet 102, whereupon the motor field and armature will be energized, as will also the brake magnet, which causes its armature 79 to be attracted and to thrust upon the rod 78 to lift the brake shoe 66 carried by the lever 68. The motor then starts and rotates the worm wheel until the crank 57 overtakes the crank 56 which is in nearly uppermost position as described, and then presses against crank 56, driving crank 51 and pulling the rod 43 downwardly to the position shown in Fig. 1, in which position the circuit breaker is locked and the brush 88 has snapped off the ring 83 at 83''. This opens the motor circuit and deenergizes the brake magnet, whereupon the springs 72 set the brake and stop the motor with the parts in position as shown in Fig. 1. Simultaneously, magnet 102 releases armature 104, and switch arm 95 returns to contact 100 under influence of centering springs 106 and 107. The apparatus is then ready to respond automatically again to the circuit breaker tripping magnets as just described. Or if it is desired to trip the circuit breaker from the distant station, the operator will throw the lever 95 into engagement with contact 101, whereupon current will flow from the positive conductor or bus bar 91 through conductor 94 to brush 89, commutator ring 84, conductor 96, energizing the motor, armature and field as before described and the brake lifting magnet, whereupon the motor will rotate to drive the cranks 51 and 52 through a short distance in a clockwise direction from its position shown in Fig. 1, whereupon the rod 43 is lifted, the bottom of the slot 41 engaging the pin 40, thus lifting the operator's lever 18, whereupon the lug 28 engages by its tail 24 upon the lip 25 of the latch 26 to disengage or unlock the circuit breaker which then opens as previously described, the extent of movement of the handle 18 with respect to member 17 being limited by its face 21 coming into contact with the face 20 on the member 17. After being thus unlocked, the circuit breaker then moves to full open position, the operator's handle being pulled upwardly, pulling the rod 43 with it and the parts assume the open circuit posi-

tion with the crank 52 just short of the dead center position at the top as previously described in connection with Fig. 1. The brush 89 has passed onto insulation 84'. So it is that the circuit breaker may be motor tripped from the distant station. Since a slight movement of the motor only is necessary for this purpose the circumferential extent of the commutator ring 84 need be relatively small only, as shown in Fig. 6, 75 while the circumferential extent of the ring 83 may be correspondingly larger. As before stated when the parts assume full open circuit position the commutator has rotated so as to bring the ring 83 again in communication with the brush 88, whereupon moving the lever 95 to the contact 99 will cause the motor to again close the breaker. Care should be taken that brush 88 can not be in contact with ring 83 at the same time brush 89 is in contact with ring 84, else conductors 91 and 92 would be short circuited. 80

What I claim is:

1. In combination, a main switch, a latch for restraining said switch in normal position, a lever for moving said switch to normal position and for actuating said latch to unlock said switch upon reverse movement of said lever, a motor operating always in one direction for actuating said lever in either direction, auxiliary switching mechanism controlling said motor, and a double throw control switch cooperating with said auxiliary switching mechanism, said control switch in one position energizing said motor 95 to actuate said latch and in the other position energizing said motor to actuate said lever in opposite direction to move said main switch to normal position. 90
2. In combination, a main switch, a latch for restraining said switch in normal position, a lever for moving said switch to normal position and for actuating said latch to unlock said switch upon reverse movement of said lever, a motor operating always in one direction for actuating said lever in either direction, and a double throw control switch and connections controlling said motor, said control switch in one position energizing said motor for actuating said latch 100 to trip said main switch, and in the other position controlling said motor to actuate said lever in opposite direction to move said main switch to normal position. 105
3. In combination, a main switch, a latch for restraining said switch in normal position, a lever for moving said switch to normal position and for actuating said latch to unlock said switch upon reverse movement of said lever, a motor operating always in one direction for actuating said lever in either direction, switching mechanism moving in definite relation with said lever for controlling said motor, and a double throw control switch controlling said motor 115 120
- 65 and the parts assume the open circuit position with the crank 52 just short of the dead center position at the top as previously described in connection with Fig. 1. The brush 89 has passed onto insulation 84'. So it is that the circuit breaker may be motor tripped from the distant station. Since a slight movement of the motor only is necessary for this purpose the circumferential extent of the commutator ring 84 need be relatively small only, as shown in Fig. 6, 75 while the circumferential extent of the ring 83 may be correspondingly larger. As before stated when the parts assume full open circuit position the commutator has rotated so as to bring the ring 83 again in communication with the brush 88, whereupon moving the lever 95 to the contact 99 will cause the motor to again close the breaker. Care should be taken that brush 88 can not be in contact with ring 83 at the same time brush 89 is in contact with ring 84, else conductors 91 and 92 would be short circuited. 80

- through said switching mechanism, said control switch in one position energizing said motor to actuate said latch and in the other position energizing said motor to move said 5 main switch to normal position and electro-responsive means for actuating said latch independently of said motor.
4. In combination, a main switch, a latch for restraining said switch in normal position, a lever for moving said switch to normal position and for actuating said latch to unlock said switch upon reverse movement of said lever, a motor operating always in one direction for actuating said lever in 10 either direction, an auxiliary switching mechanism movable in definite relation with said lever, said switching mechanism having a contact controlling energization of said motor for actuating said latch to trip said 15 main switch and another contact controlling energization of said motor for moving said main switch to locked position and means for actuating said latch independently of said motor.
- 20 5. In combination, a main switch, a latch for restraining said switch in normal position, a lever for moving said switch to normal position and for actuating said latch to unlock said switch upon reverse movement of 25 said lever, a motor operating always in one direction for actuating said lever in either direction, an auxiliary switching mechanism movable in definite relation with said lever, said switching mechanism having a contact 30 controlling energization of said motor for actuating said latch to trip said main switch and another contact controlling energization of said motor for moving said main switch to locked position, and a double throw 35 40 control switch controlling said motor through said auxiliary switching mechanism, and electro-responsive means for actuating said latch independently of said motor.
6. In combination, a main switch, a latch 45 for restraining said switch in normal position, a lever for moving said switch to normal position and for actuating said latch to unlock said switch upon reverse movement of said lever, a motor operating always in 50 one direction for actuating said lever in either direction, a lost motion connection between said motor and said lever whereby when said latch is actuated said main switch may move independently of said motor, and 55 auxiliary switching mechanism movable in definite relation with said lever controlling successive energizations of said motor for actuating said latch and for moving said main switch to locked position, and electro-re- 60 65 sponsive means for actuating said latch independently of said motor.
7. In combination, a main switch, a latch for restraining said switch in normal position, a lever for moving said switch to normal 70 position and for actuating said latch to

unlock said switch upon reverse movement of said lever, a motor operating always in one direction for actuating said lever in either direction, a lost motion connection between said motor and said lever whereby when said latch is actuated said main switch may move independently of said motor, auxiliary switching mechanism movable in definite relation with said lever controlling successive energizations of said motor for actuating said latch and for moving said main switch to locked position, and an operator's switch controlling said motor through said auxiliary switching mechanism, and electro-responsive means for actuating said latch independently of said motor. 75

8. In combination, a main switch, a latch for restraining said switch in normal position, a lever for moving said switch to normal position and for actuating said latch to unlock said switch upon reverse movement of said lever, a motor operating always in one direction for actuating said lever in either direction, a lost motion rod and crank connection between said motor and said lever, whereby said main switch when tripped by actuation of said latch moves independently of said motor, and auxiliary switching mechanism movable in definite relation with said lever controlling successive energizations of said motor to actuate said latch and return said main switch to normal position, and electro-responsive means for actuating said latch independently of said motor. 80

9. In combination, a main switch, a latch for restraining said switch in normal position, a lever for moving said switch to normal position and for actuating said latch to unlock said switch upon reverse movement of said lever, a motor operating always in one direction for actuating said lever in either direction, a lost motion rod and crank connection between said motor and said lever, whereby said main switch when tripped by actuation of said latch moves independently of said motor, auxiliary switching mechanism movable in definite relation with said lever controlling successive energizations of said motor to actuate said latch and return said main switch to normal position, and an operator's switch controlling energization of said motor through said auxiliary switching mechanism, and electro-responsive means for actuating said latch independently of said motor. 85

10. In combination, a main switch, a latch for restraining said switch in normal position, a motor operating always in one direction for actuating said latch to trip said main switch and to return said main switch to normal position, and auxiliary switching mechanism movable in definite relation with said main switch controlling successive energizations of said motor for tripping said main switch and returning the same to nor- 90 95 100 105 110 115 120 125 130

- mal position, and electro-responsive means for actuating said latch independently of said motor.
11. In combination, a main switch, a latch for restraining said switch in normal position, a motor operating always in one direction for actuating said latch to trip said main switch and to return said main switch to normal position, auxiliary switching mechanism movable in definite relation with said main switch controlling successive energizations of said motor for tripping said main switch and returning the same to normal position, and an operator's switch controlling said energizations of said motor through said auxiliary switching mechanism, and electro-responsive means for actuating said latch independently of said motor.
12. In combination, a movable contact member, means for operating said contact member, a motor, a rod and crank connection with said operating means driven by said motor, and a stop moving in definite relation with respect to said motor for preventing said rod and crank connection assuming a dead center position.
13. In combination, a movable contact member, a rod and crank connection with said contact member, a motor, a second crank driven thereby, a lost motion connection between said cranks, and a stop on said second crank for preventing said rod and crank connection assuming dead-center position.
14. In combination, an electric switch, an actuator therefor to move the same to normal position, means for restraining said switch in normal position, a motor, a rod and crank connection with said actuator, a lost motion connection between said motor and said rod and crank connection, means on said actuator for releasing said switch, and means for preventing said rod and crank connection assuming dead-center position.
15. In combination, an electric switch, a latch for restraining the same in normal position, an actuator for moving said switch to normal position and for actuating said latch upon reverse movement, a motor for operating said actuator in both directions, and a switch moving in unison with said first named switch and connected in the circuit of said motor for breaking the motor circuit when said electric switch has reached circuit closing position and for closing the circuit of said motor for tripping said electric switch, and electro-responsive means for actuating said latch independently of said motor.
16. In combination, a motor, a crank driven thereby, a movable contact member of a switch, means for operating the same, an actuator having limited motion with respect to said operating means, a rod and crank connection with said actuator, said first men-
- tioned crank having lost motion with respect to said rod and crank connection, and means on said first mentioned crank for preventing said rod and crank connection assuming dead-center position.
17. In combination, an electric switch, means independent of the operating mechanism for said switch for restraining the same in normal position, a lever for moving said switch to normal position and for actuating said restraining means upon reverse movement, a motor for actuating said lever in either direction, and motor controlling contacts movable in definite relation with the moving parts of said switch, one of said contacts controlling said motor for actuating said lever in one direction, and the other contact controlling said motor for actuating said lever in reverse direction.
18. In combination, an electric switch, means independent of the operating mechanism for said switch for restraining the same in normal position, a lever for moving said switch to normal position and for actuating said restraining means upon reverse movement, a motor operating always in one direction for actuating said lever in either direction, and motor controlling contacts movable in definite relation with the moving parts of said switch, one of said contacts controlling said motor for actuating said lever in one direction, and the other contact controlling said motor for actuating said lever in reverse direction.
19. In combination, an electric switch, means independent of the operating mechanism for said switch for restraining the same in normal position, a lever for moving said switch to normal position and for actuating said restraining means upon reverse movement, a motor for actuating said lever in either direction, motor controlling contacts movable in definite relation with the moving parts of said switch, one of said contacts controlling said motor for actuating said lever in one direction, and the other contact controlling said motor for actuating said lever in reverse direction, and a lost motion connection between said motor and said lever, whereby said switch moves independently of said motor when tripped thereby.
20. In combination, an electric switch, means independent of the operating mechanism for said switch for restraining the same in normal position, a lever for moving said switch to normal position and for actuating said restraining means upon reverse movement, a motor operating always in one direction for actuating said lever in either direction, motor controlling contacts movable in definite relation with the moving parts of said switch, one of said contacts controlling said motor for actuating said lever in one direction, and the other

contact controlling said motor for actuating said lever in reverse direction, and a lost motion connection between said motor and said lever, whereby said switch moves independently of said motor when tripped thereby.

21. In combination, a movable contact member, a latch therefor, an actuator for actuating said latch or said contact member, a rod and crank connection with said actuator, a motor, a second crank driven thereby, a lost motion connection between said cranks, means preventing said rod and crank connection assuming a dead-center position, and motor controlling contacts movable in definite relation with said rod and crank connection, and a remote switch controlling said motor.

22. In combination, an electric switch, means for restraining said switch in normal position, a member for moving said switch to normal position and for actuating said restraining means upon reverse movement, a motor for actuating said member, and motor controlling contacts moved when said switch is moved, said contacts affecting the control of said motor for different periods, one of said contacts controlling said motor for movement of said switch to normal position, and another of said contacts controlling said motor for a shorter period for actuating said restraining means.

23. In combination, an electric switch, operating means therefor, an electric motor for moving said operating means in either direction, and motor controlling contacts controlling said motor for different periods, one of said contacts controlling said motor to move said operating means in one direction, and another of said contacts controlling said motor for a shorter period for operating said operating means in opposite direction.

24. In combination, an electric switch, an operating member therefor, a motor for actuating said operating member in either direction, a lost motion connection between said motor and said operating member, and controlling contacts movable in definite relation with respect to said operating member and controlling said motor for different periods of time, one of said contacts controlling said motor for moving said operating member in one direction, and another of said contacts controlling said motor for a shorter period for actuating said operating member in opposite direction for tripping said switch.

25. In combination, a main switch, a latch for restraining said switch in normal position, a lever for moving said switch to nor-

mal position and for actuating said latch to unlock said switch upon reverse movement of said lever, a motor, a gear driven thereby, said gear permanently connected with said motor, a lost motion connection between said gear and said lever, auxiliary switching mechanism controlling said motor, and a double throw control switch controlling said motor through said switching mechanism for actuating said latch or moving said main switch to normal position.

26. In combination, a main switch, a latch for restraining said switch in normal position, a lever for moving said switch to normal position and for actuating said latch to unlock said switch upon reverse movement of said lever, a motor, a gear driven thereby, said gear permanently connected with said motor, a lost motion connection between said gear and said lever, auxiliary switching mechanism controlling said motor, a double throw control switch controlling said motor through said switching mechanism for actuating said latch or moving said main switch to normal position, and electro-magnetic means for actuating said latch independently of said motor.

27. The combination with a circuit breaker having a trip coil, of a motor for actuating said breaker, an operator's switch controlling said motor, an electro-magnet brought into circuit by and retaining said operator's switch, and a switch controlling the circuit of said motor and said electro-magnet actuated in response to the operation of said trip coil.

28. In combination, a main switch, a latch for restraining said switch in normal position, a lever for moving said switch to normal position and for actuating said latch to unlock said switch upon reverse movement of said lever, a motor for actuating said lever to trip said switch and to return the same to normal position, electro-magnetic means for actuating said latch independently of said motor, a double throw operator's switch controlling said motor, an electro-magnet brought into circuit by and retaining said operator's switch in both its positions, and a switch controlling the circuit of said motor and said electro-magnet actuated in response to the tripping of said main switch.

In testimony whereof I have hereunto affixed my signature in the presence of the two subscribing witnesses.

WILLIAM M. SCOTT.
